PHASE EQUILIBRIUM COMPUTER

Joseph D. Eisler and Elihu H. Cooley, Tulsa, Okla., assignors to Stanolind Oil and Gas Company, Tulsa, Okla., a corporation of Delaware

Application August 20, 1952, Serial No. 305,322

5 Claims. (Cl. 235—61)

This invention relates to a special type of electrical computer of particular application to problems involving phase-equilibrium data in chemical engineering computations.

In many aspects of the crude oil producing and refining industries, the physical behavior of petroleum fluids under various conditions of pressure and temperature is of great importance. The liquid-vapor phase relationships are of controlling interest in the design of fractionators, absorbers, surface separator systems, analysis of reservoir fluids with pressure decline, recovery problems, etc.

In fractionators and absorbers, the quantitative interactions of the gas and liquid phases are important as functions of the pressure variation throughout the columns, or as functions of the absolute pressure and temperature operating variables.

In oil production operations, the nature and amount of gas developed in the reservoir with pressure decline depends on the basic liquid-vapor relationships. The bubble points and dew points of hydrocarbon fluids determine conditions of pressure and temperature at which the first bubble of vapor, or the first drop of liquid, will form, respectively. The amount of gas in solution per barrel of residual oil at 60° F. and one atmosphere, commonly known as the gas-oil ratio, is of importance in estimating the behavior of reservoir fluids as the reservoir pressure declines, and in material balance calculations. One of the best ways to follow the process of changing oil and gas compositions and amounts with reservoir pressure decline is by means of pressure-temperature diagrams of the fluids, or the so-called "phase diagrams."

Surface-separator systems may be designed using proper mathematical relations expressing the liquid-vapor phase interactions. Optimum operating pressures and temperatures for maximum recovery of the desirable constituents can be computed, together with the stock tank losses.

The physical phenomena associated with the vapor-liquid relationships can, in each instance, be evaluated by appropriate experimental methods which are both laborious and time-consuming. However, by ascribing to each individual component certain characteristics describing the vapor-liquid behavior, the phase properties of the composite mixtures can be mathematically expressed and computed.

The fundamental mathematical relationships involved in problems in phase-equilibrium data are given below:

$$\Sigma x_n = 1 \quad (1)$$

$$\Sigma y_n = 1 \quad (2)$$

$$\Sigma z_n = 1 \quad (3)$$

$$V + L = 1 \quad (4)$$

in which:

n =ordinal number of the constituents in a given system,
 x_n =mol fraction of any constituent in liquid form;

2

y_n =mol fraction of any constituent in vapor form,
 z_n =mol of any constituent per mol of feed,
 L =mols of total liquid per mol of feed,
 V =mols of total vapor per mol of feed.

5 For material balance for any constituent,

$$z_n = Vy_n + Lx_n \quad (5)$$

The equilibrium vaporization factor for any constituent equals the ratio of y_n to x_n and its value at any given temperature and pressure is given in published tables. Thus,

$$\frac{y_n}{x_n} = k_n \quad (6)$$

$$\frac{L}{V} = Q \quad (7)$$

in which Q is a factor convenient for use in the computer arrangement, as will appear below.

By substituting Equations 6 and 7 into Equation 5 and summing for n constituents,

$$\Sigma Vx_n = V = \Sigma \frac{z_n}{k_n + Q} \quad (8)$$

From Equation 4 and Equation 7,

$$V = \frac{1}{1 + Q} \quad (9)$$

30 Combining Equations 8 and 9,

$$\frac{1}{1 + Q} = \Sigma \frac{z_n}{k_n + Q} \quad (10)$$

This equation is the basic computer equation.

In solving a given problem, the values of z_n and k_n are introduced into the computer and a value of Q is found by electrical balance which satisfies Equation 10. Once the value of Q is determined, the value of V is obtained by another electrical balance based on Equation 9. The value of x_n for each individual constituent may be obtained by an electrical balance based on the individual terms of Equation 8. The value of L and the individual values of y_n can be determined from Equations 4 and 6 respectively by calculation.

45 It will be shown that by use of the Equation 10, it is possible to set up a multiple bridge circuit which permits determining the unknown factors (usually x_n and V) in a given problem, in a time much less than that required for the previous tedious cut-and-try approximations now in use.

50 In order to illustrate the design and operation of the invention, certain figures are attached, which form a part of this specification. In these figures, the same reference numeral in different figures refers to the same or a corresponding part.

55 Figure 1 shows a circuit used to obtain a voltage proportional to the quantity

$$\frac{z_n}{k_n + Q}$$

60 Figure 2 shows a circuit used to obtain a voltage equal to the sum

$$\Sigma \frac{z_n}{k_n + Q}$$

equal to the right side of Equation 8 or 10. Only part of the circuit is shown; that not shown consists of further units of the type given in Figure 1.

65 Figure 3 shows a circuit used to obtain a voltage proportional to

$$\frac{1}{1 + Q}$$

70 the left side of Equation 10.

Figure 4 shows a circuit involving those of Figures 2 and 3 for solving Equation 10. As in Figure 2, only part of the circuit is shown, that not shown consisting of further units of the type given in Figure 2.

Figure 5 shows the circuits of one complete computer arranged in accordance with this invention.

The choice of the form of phase equilibrium relationship, as given above, permits the design of a suitable network of resistors which together with a null indicator forms the computer. For convenience of operation, each factor in the equation may be represented by a decade variable precision resistance. The resistances possess the necessary stability in order to achieve the required accuracy of the final solution.

In tracing the correspondence between the liquid-vapor system and the computer circuit, the portion of the circuit representing one term of the sum given by the right-hand part of Equation 10, is given in Figure 1. The two factors z_n and

$$\frac{1}{k_n+Q}$$

are represented by a resistance and a current respectively, so that their product becomes a voltage. In the term

$$\frac{1}{k_n+Q}$$

the two variables in the denominator are represented by two variable resistors k_n (12) and Q (13) connected in series. The current in this path is

$$\frac{1}{k_n+Q}$$

per volt applied to that path. A convenient resistance scale factor of 10,000 ohms may be chosen, for example, to represent unity in the equation. The factor z_n is introduced into this relationship by tapping a portion of the resistance representing Q . While the total value of Q remains unchanged, the tap 15 on the potential divider provides control for z_n . The resistance from the bottom of this potentiometer 16 up to the tap 15 is made proportional to z_n , using the scale factor mentioned. Thus, the voltage e_{15-16} across z_n is proportional to the product required by Equation 10. The right-hand part of Equation 10 is a sum of terms representing all the constituents in a given system, and additional similar paths are set up in the computer, in parallel, to represent the other constituents. While the setting values of k_n and z_n may be different in each of these branches, the value of Q is the same in all paths and the Q controls for all paths are mechanically coupled to one set of control knobs, for example, by means of sprockets and chains. Thus, all Q resistors 13 are simultaneously changed at the same rate by the same amount.

To obtain the sum of all constituents as given by the right-hand side of Equation 10, voltages from all the z_n taps are added electrically by employing substantially identical high resistances S (19) connected to a common mixer point 20. The voltage to ground at this common point 20 represents the entire right-hand side of Equation 10. The schematic connection of that portion of the equation is given in Figure 2. In this figure, resistances 17 and total potentiometer resistances 18 in series make up the Q resistors.

The requirements on the values of the high resistances S in order that the voltage e_{20-16} across the points 20 to 16 of Figure 2 shall be proportional to the sum

$$\sum \frac{z_n}{k_n+Q}$$

are that they be substantially identical in resistance and that the value of the resistances be large compared with the total resistance connected in series with each such resistance, at least about 100 times and preferably 1,000 times such series resistance. (See "A Twelve-Equation Computing Instrument" by Berry and Pemberton, Instru-

ments, vol. 19, No. 7, July 1946, pp. 396-7, or U. S. 2,557,070 Berry.)

It should be pointed out that it is immaterial whether the Q resistor or the k_n resistor is tapped at the value proportional to z_n . In both cases, the voltage produced will be proportional to

$$\frac{z_n}{k_n+Q}$$

10 The bridge circuit is completed by providing a path corresponding to the left-hand portion of the equation; namely,

$$\frac{1}{1+Q}$$

15 The circuit for this path is given in Figure 3. The denominator of the equation is represented by two resistors Q (13) and R (23) (R being equal to unity on the scale chosen—in the example given, equal to 10,000 ohms).

20 The Q resistor 13 is mechanically coupled to the gang of resistances for the Q on the other side of the bridge. The current through this path per volt applied to the bridge is

$$\frac{1}{1+Q}$$

25 and the voltage across the unity portion R from 21 to 16 is thus equal to the current.

30 To achieve the "equal" sign in the Equation 10, the voltage

$$\frac{1}{1+Q}$$

35 must be reduced by an appropriate scale factor m . It is apparent that when point 22 is eventually connected to the null balance detector 24 shown in Figures 4 and 5 and final balance is obtained by suitable manipulation of the Q resistors, the voltage drop e across points 20 to 16

40 is balanced by e' across 22 to 16, and no current flows through point 20. At this point, the current flow due to the voltage across the z_1 resistance must return to ground through $n-1$ S resistances 19 in parallel. The voltage component e across 20-16 at this time due to that across 45 z_1 is thus across a voltage divider of $n-1$ S resistors 19 in parallel, in series with one S resistor, so the voltage component across 20-16 is

$$\frac{1}{n}$$

50 that across z_1 . Since this applied to all such components, the voltage e across 20-16 is thus

$$55 e = \frac{E}{n} \sum \frac{z_n}{k_n+Q} \quad (11)$$

In this case, the appropriate scale factor m is numerically equal to n .

60 However, a further improvement can be made. This results from the fact that Q should desirably have values less than 1, in fact down to about 0.01. This can be accomplished by making the z_n resistances 18 proportionally less than would be indicated by the circuit of Figure 1. If, for example, the maximum value of z_n is 0.01 of the 65 value it nominally should have, then Q can have a minimum value of 0.01, since the minimum value of the Q resistances is the maximum value of a z_n potentiometer. In this case, the voltage

$$70 e = \frac{0.01 E}{n} \sum \frac{z_n}{k_n+Q} \quad (12)$$

75 and the appropriate scale factor m is numerically equal to 100 n . Other values for the z_n potentiometers obviously could be used; the example given is merely illustrative.

When m has been determined in the design, a tap 22 can be established on the resistor 23 at

$$\frac{1}{m}$$

the value of this resistance from the bottom. Then

$$e' = \frac{E}{m} \frac{1}{1+Q} \quad (13)$$

A null detector 24 (voltmeter, galvanometer, etc.) preferably with adjustable sensitivity is connected from point 20 to point 22. When by simultaneous manipulation of all the Q resistors the voltage across the null detector 24 becomes zero, e is equal to e' , or

$$\sum \frac{z_n}{k_n + Q} = \frac{1}{1+Q} \quad (14)$$

By reference to Equation 10 it is seen that this was the equation to be solved, and the true value for Q has been found. At any other value of Q , the null indicator 24 will show a voltage across it.

The problem is introduced into the computer by setting the proper value for the z_n potentiometers 18 and k_n resistors 12 for all constituents. The problem is solved by varying the ganged Q resistances until the potential across the null indicator 24 is zero. The value of Q at balance may be read from dials on a panel (e. g., by adding the value 0.01, the minimum, to the dial reading of the decade Q resistors 17). Convenient ranges for the z_n potentiometers 18 are four decades and for the k_n resistors 12, seven decades. The values of k_n are adjusted to literature values by setting the appropriate decades. The values for z_n (or proportional part, as discussed above) are similarly adjusted to the mol fraction of the feed for the particular constituent.

While the balancing of Q resistors represents the solution to a given problem, there are voltages at the various points in the circuit which yield additional required answers. The voltage across unity resistance 23 (R) on the right-hand side of the bridge corresponds to V in terms of the bridge voltage (see Figure 3); and the voltage across each z_n corresponds to x_n in terms of the V voltage. The values of V and x_n are evaluated by balancing these voltages against calibrated potential divider circuits.

This is explained in more detail by reference to Figure 5. In Equation 9 the value V is shown to be

$$\frac{1}{1+Q}$$

The voltage at point 25 for a 10 constituent computer, that is, $n=10$, is

$$e' = 0.001 E \frac{1}{1+Q} \quad (15)$$

Since a null detector 24 is available, it is only necessary to employ this detector and a suitable potentiometer circuit to measure V . This potentiometer circuit is made up of potentiometer 26 and series resistor 27, arranged of such values that the voltage across 26 is 0.001 E . By suitable manipulation of multipoint selector switch 28 to position 11 at the left, the voltage on the tap of potentiometer 26 is applied in series opposition to that from point 25. By changing this tap on potentiometer 26 (usually but not necessarily by making 26 a three or four decade potentiometer and adjusting the dials) until a null is obtained, and reading the potentiometer setting, the value of

$$\frac{1}{1+Q}$$

or V , is obtained.

The values of the various x 's can also be found. By reference to Equation 8

$$V z_n = \frac{z_n}{k_n + Q}$$

$$\frac{1}{1+Q} z_n = \frac{z_n}{k_n + Q} \quad (16)$$

5 The voltage across the tap of each z_n potentiometer is either

$$E \frac{z_n}{k_n + Q}$$

or as explained earlier, some fixed fraction of this amount. In Figure 5, it is

$$0.01 E \frac{z_n}{k_n + Q}$$

The total voltage across each of the so-called x_n potentiometers 29 is arranged to be that same fixed fraction of the voltage across the R resistor 23, which is

$$E \frac{1}{1+Q}$$

Thus, in the circuit of Figure 5, by using 100 ohm potentiometers 29, the total potentiometer voltage is

$$0.01 E \frac{1}{1+Q}$$

When the x_n potentiometers 29 are individually switched into the null detector circuit by switch 28, the variable voltage on the potentiometer 29 tap opposes the output voltage of the corresponding z_n resistor 18. By varying the tap of potentiometer 29 (again usually but not necessarily by making each such x_n potentiometer 29 a three or four decade arrangement, and adjusting the dials) until the null detector 24 shows no voltage, the x_n potentiometer 29 is set at the correct value, given by Equation 16. This value of x_n can then be read off the dials of the potentiometer 29.

In one typical computer designed for 10 constituents, the various resistors had the following values:

	Type	Value or Range
k_n		0.1 to 1,000,000 ohms (7 decades).
Q		same.
z_n		0.01 to 100 ohms (4 decades).
S		same.
R		100,000 ohms.
		10,000 ohms.

The voltage source E was approximately 200 volts, and the null detector was a four stage amplifier and meter with a 10 per cent full scale reading for a D. C. input of about five microvolts. With these components, it is conservatively estimated that the computer gave x_n accurate to $\pm 0.05\%$ of the total liquid and V accurate to $\pm .05$ of the total batch. Three representative problems are given below for which the precision of the answers given by the computer are compared to the calculated values.

	Constituent	z_n	k_n	x_n (Computer)	x_n (Calculated)

			$V = .1683$	

The time required for the solution of these representative problems was about five minutes. About half of this time was taken up in setting the given data into the machine. This time is greatly decreased for the type of problems where a study is made on the behavior of the mixture for various temperatures and pressures. For such a problem, the z_n settings would not be changed and the solution is carried out for successive settings of k_n values. It is apparent that this is very much less than the present cut-and-try methods, requiring about half an hour to an hour and a half for solution with an experienced computer.

Instead of using decade resistances, adjustable resistances can be employed, in which case, for example, a simple Wheatstone bridge can be set up using the same null detector, if desired, and one multidecade resistor, and set each k_n and z_n resistor by comparison, from this bridge. If desired, a servomechanism can be used to adjust these values automatically. The Q values can be given by ganged multiple rotation variables resistors such as those sold under the trade name Helipots or the like, and the Wheatstone bridge can be used for determining the ultimate, correct value of Q .

It is to be especially noted that the circuits in the computer are entirely potentiometric or bridge type in operation, and that accordingly the value of the potential E of the voltage source does not affect the accuracy of the computer, nor are ordinary variations in this value of importance. It is also apparent that alternating current as well as direct current sources could be used, with suitable changes in the null detector, as are well-known in the art. Of course, in the A. C. case, it is necessary that the impedance of all similar elements, such as the S add resistors, must all be alike, so that the currents through each of the series circuits in Figures 1, 2, and 3 are identical in phase.

While this invention has been described with reference to certain specific embodiments, it will be readily apparent to those skilled in the art that variations and modifications may be made without departing from the teaching given. The invention is best defined by the scope of the appended claims.

We claim:

1. A computer circuit including a plurality n of adjustable resistors, $n+1$ ganged variable resistors simultane-

ously variable at equal rates, n potentiometers each individually adjustable, each of said adjustable resistors being connected in series with one only of said ganged variable resistors and one only of said potentiometers, the remaining one of said variable resistors being connected in series with a fixed potentiometer, a voltage source connected in parallel to the n series circuits each containing one of said adjustable resistors and also connected across said remaining variable resistance and said fixed potentiometer, n substantially equal fixed resistors each having a value large compared with the maximum values of said n potentiometers, and a voltage detector connected to the tap of said fixed potentiometer and to one end of each of said fixed resistors, the other ends of said fixed resistors being individually connected to the taps of each of said n potentiometers.

2. A computer circuit including a source of voltage, a plurality of circuits in parallel across said source, similar components of each of said circuits being substantially equal, said components consisting of an adjustable resistor, a variable resistor, and an adjustable potentiometer in series, a number equal to the number of said circuits of substantially equal fixed resistors each individually connected to the tap of one only of said adjustable potentiometers at one end and connected together at the other end, a separate circuit consisting of a fixed potentiometer connected in series with a variable resistor substantially equal to the similar component in one of said circuits, said separate circuit being connected across said source of voltage, a voltage detector connected to the common connection to all of said substantially equal fixed resistors and to the tap of said fixed potentiometer, and means for simultaneously varying at equal rates the magnitudes of all said variable resistors.

3. An electrical computer circuit for solving the equation

$$\frac{1}{1+Q} = \sum \frac{z_n}{k_n + Q}$$

40 where Q is initially unknown while z_n and k_n are n pairs of known quantities, comprising a source of voltage, a plurality $n+1$ substantially identical ganged variable resistors, whereby their magnitudes may be simultaneously varied at equal rates, a plurality n individually adjustable resistors the maximum magnitude of which is approximately equal to that of said variable resistors, a plurality n individually adjustable substantially equal potentiometers, each of said adjustable resistors being individually connected in series with one only of said variable resistors and one only of said potentiometers across said source of voltage, means for adjusting the resistance of each of said adjustable resistors directly proportional to each one of said quantities k_n , means for adjusting the setting of said n potentiometers directly proportional to the value z_n corresponding in subscript to the value k_n for which the adjustable resistor connected to each said potentiometer was adjusted, a fixed resistor connected in series with the remaining variable resistor, said fixed resistor having its resistance proportional to the value unity by the same factor as the resistance of the adjustable resistors bears to the values in series with said fixed resistor and said remaining variable resistor across said source of voltage k_n , an additional potentiometer connected in series with said fixed resistor for producing a voltage across said additional potentiometer in a ratio to the total voltage across said fixed resistor as

$$\frac{1}{n}$$

70 times the ratio of the setting of any of said adjustable potentiometers to the corresponding value z_n , a plurality n of substantially identical fixed resistors large in magnitude compared with the maximum value of any of said n potentiometers, one end of said fixed resistors being individually connected to the tap on one of said n po-

tentiometers, and an electrical null detector connected in series opposition between the other ends of all said fixed resistors and to the tap of said additional potentiometer, said additional potentiometer, fixed resistor, and one of said identical ganged variable resistors being connected in series across said source of voltage whereby simultaneous variation of said variable resistors until said null detector reads zero produces a resistance in each of said variable resistors directly proportional to the value Q satisfying said equation.

4. Apparatus in accordance with claim 3 including a variable potentiometer and multiple pole switching means for applying across said variable potentiometer a voltage proportional to

$$\frac{1}{1+Q}$$

and for connecting the output of said potentiometer across said null detector in series opposition with the voltage output of one of said n potentiometers while simultaneously disconnecting said detector from said n fixed resistors and

from said resistance means, whereby the voltage output of said one of said n potentiometers can be determined relative to said voltage proportional to

$$\frac{1}{1+Q}$$

5. Apparatus in accordance with claim 4 including potentiometric means for measuring said voltage proportional to

$$\frac{1}{1+Q}$$
